EARTH BORING APPARATUS

Alan Jay Parrish, Paris, Ill.

Application October 21, 1940, Serial No. 362,139

9 Claims. (Cl. 255—21)

This invention relates to portable earth boring apparatus and more particularly to apparatus for effecting rapid and accurate earth borings at controlled angles in respect to a mobile support.

One of the objects of the invention is the provision of an apparatus for making accurate earth borings at controlled angles from a transport vehicle for demolition work, for borings along highways and for general boring operation accessible to the machine.

Another object of the invention is the provision of a boring machine and supporting base structure providing vertical swinging adjustments to desired angles for drilling operations.

A further object of the invention is the provision of a boring machine and cooperating base assembly carrying said machine in a retracted loaded position or in a forward pivotal drilling position.

A further object is the provision of a controlled angle drilling apparatus having self-adjusting driving means.

Further objects include the provision of manually operable means for moving the machine on its base and an improved adjustable motor mounting means.

In carrying out these objects, and others which will become apparent from the description of the invention, there is provided apparatus which will be better understood from the following detailed description having reference to the accompanying drawings wherein.

Fig. 1 is a view in side elevation of an embodiment of the invention with the drilling unit shown by full and dotted lines in different positions of adjustment.

Fig. 2 is a view in side elevation of the apparatus of Fig. 1, with the boring unit in retracted or loaded position.

Fig. 3 is a broken end view showing in plan the machine mounting and base.

Figs. 4 and 5 are sectional views, respectively, taken on lines 4—4 and 5—5 of Fig. 3.

Fig. 6 is a rear broken perspective of the machine and its mounting in the dotted line position of Fig. 7.

Fig. 7 is a detail longitudinal section showing mounting details of the machine base and sub-base, and Fig. 8 is a perspective view of the detachable mounting plate.

Fig. 9 is a central vertical section of the cable winding device of Figs. 1 and 2.

Fig. 10 is a transverse end view partly in section illustrating the boring unit and base

assembly details, and Fig. 11 is a vertical section taken on line 11—11 of Fig. 10.

Figs. 12 and 13 are enlarged fragmentary views in side and end elevation, respectively, illustrating motor base and mounting details.

Fig. 14 is a view on line 14—14 of Fig. 12, showing the top plan of the motor support, and Fig. 15 is a transverse section on line 15—15 showing roller and king bolt details.

Fig. 16 is a detail sectional view taken on line 16—16 of Fig. 12.

Referring to the drawings, there is illustrated in Figs. 1 and 2 thereof in particular, earth boring apparatus for controlled angle earth borings in an arc extending over 90° from a substantially perpendicular position to a position above the horizontal. In this apparatus, a vehicle 1, preferably of the conventional motor driven type provides mobility and carries a platform support 2, having fixed thereto in overhanging relationship at one side or another, an inclined boring machine supporting base 3. This base, for economy of construction and strength, consists of the parallel formed standard channel sections 4 and 5 having inwardly facing flanges and depending portions overlying the sides of the vehicle support. Portions of the channels overlying the vehicle support have welded thereto cross tie plate 6 extending laterally beyond the channels, these extensions being apertured to receive the fastening bolts 7. The upper ends of the channels are each closed by a welded plate 8 supporting aligned pivot bearings 9 for the machine supporting removable pivotal pin 10 and the channels are apertured in alignment to receive the removable fastening pin 11. Horizontal rearwardly extending parallel angles 12 and inclined angles 13 have their meeting ends fitted together and welded, these ends being maintained in spaced parallel relationship by the underlying tie plate 14 with lateral extensions for fastening bolts 15. The angle members are secured by welding to the channel members. Inclined angles 13 have inwardly facing flanges which, at a predetermined distance from the pivot bearings, are provided with seating depressions 16 to receive wheels on the earth boring unit mounting means presently to be described.

The earth boring unit 17 is movably mounted on base 3 to occupy a retracted or loaded position as shown in Figure 2, or an advanced or pivoted position supported by pin 10, as shown in Figure 1. The boring unit is of the type described and claimed in my copending applica-

tion Serial No. 348,577, filed July 30, 1940, and consists of a guiding base channel trackway of spaced parallel channel members 19 and 20, with underlying cross channel tie members 21 and longitudinally extending rack bars 22 along the upper flanges of the channels for meshing engagement with feed pinions 23 extending at opposite sides of boring unit 17. Each channel has longitudinally extending angle members 24 and 25 welded to the channel webs to define a relatively narrow slot or trackway adapted to slidably receive, support and accurately guide the boring unit.

The boring unit includes a frame 26 and base 27 of welded structural members. The base is of less width than the distance between inwardly directed flanges of the base to permit free longitudinal movement of the unit in the trackway. Horizontal flanges 28 welded to the base are slidably received in the trackway for adjustably supporting the unit, the fits between the flanges being such as to provide free but accurate longitudinal movement of the unit along the base. A boring tool drive shaft 29 extends longitudinally of the unit base driven by chain sprocket 30 and carries a combined chuck and flexible coupling 31 having detachable driving connection with auger 18. The boring tool shaft has power transmission connection with flexible drive shaft 32 through reduction gearing including a series of chains and sprockets. The gearing is such as to provide a large gear reduction ratio for transmission of substantial power from the flexible drive shaft.

Sliding movement of the boring unit longitudinally of the base is accomplished only by manually operated feed means. Movement of the unit is produced by rotating pinions 23 fixed to pinion shaft 33 carrying sprocket 34 fixed to the shaft and combined worm gear and clutch 35 rotatably mounted on the shaft but selectively engageable with clutch member 36 through manually operable lever means 37. Sprocket 34 is connected through low ratio chain and sprocket connection to shafts 38 and 39 adapted to receive hand wheel 40, rotation of which provides for rapid movement of the unit along the base when the worm gear clutch is disengaged. Shafts 38 and 39 are connected by gear reducing sprockets and cooperating chain to provide two optional gear reductions usable in different positions of the machine. Hand wheel 40 may be used on either of the shafts 38 or 39. Worm gear 35 is driven by worm 41 fixed to shaft 42 driven by hand wheel 43, and provides a relatively high gear reduction ratio of approximately 25 to 1, employed mainly during drilling operations where slow progress is necessary. The high ratio feed presents such mechanical advantage and sensitive control that the boring unit easily progresses during the most exacting drilling operations by only a slight pressure on the hand wheel. The feed mechanism is so sensitive and easily manipulated and the unit is so accurately guided that an operator is enabled to accurately feel drilling conditions throughout a drilling operation. This is not possible with machines having automatic feed arrangements.

The boring machine hereinbefore described is mounted on base 3 for retractible and swinging movement by a sub-base 44. This base consists of a box structure of interfitted standard channel members 45 and 46 welded together with their flanges in overlapped position and with web portions of the channels forming top and

bottom sides of the box structure. Sides of the box member of the sub-base are apertured in alignment at spaced positions to receive the removable supporting pivot pin 10, removable pins 47 and 48, and shaft 49 carrying on opposite sides of the box structure flanged wheels 50 and 51, so spaced as to engage and ride on inclined angle members 13 of the base 3 when the machine is swung on supporting pivot pin 10. A series of vertically aligned apertures 52 through the web portions of the channel members 45 and 46 are adapted to register with central apertures in the base tie channel 21 and those of an interposed wear plate 53 and an overlying bracket or clamping plate 54 to receive bolt 55 fastening the machine to the sub-base in such manner as to allow a lateral swinging or pivotal movement of the machine on bolt 55. Clamping plate 54 overlies cross-tie channel 21 and is provided at its ends with depending ears 56 which are apertured and straddle the channel member box frame to receive the removable pins 47 and 48. By this arrangement the machine is securely mounted on the sub-base but is capable of swinging movement in a direction at right angle to that provided by the pivotal support of the sub-base on pivot pin 10. The forward end of the machine is supported on the sub-base by arcuate angle member 57 having its flange portions connected by welding to the sub-base box frame, filler piece 58 forming the supporting welded connection between the horizontal flange portion and the base frame. The ends of the angle member are provided with a series of spaced apertures 59 adapted to receive manually releasable spring pressed latch bolts 60 fixed to the sides of the machine base channels. These latch bolts serve to fix the machine in a position of adjustment when swung about the bolt 55 and wear plate 53 accommodates base channel 21 in the swinging movement. The arcuate angle member has pivotally mounted thereon on its under or rear side spaced supports 61 positioned to slidably engage opposite sides of the base 3. These supports are provided with a series of spaced apertures adapted to receive the removable pin 11 for angular adjustment of the machine when tilted on pivot pin 10. In the arrangement described, the machine can be angularly adjusted in two directions about pivot pin 10 and bolt 55. Wheels 50 and 51 are so spaced with respect to pivot pin 10 that when the machine is swung downwardly at its rear end to engage base 3 the wheels enter depressions 16 in the inclined channels. With the machine in this position, pivot pin 10 can be removed to allow the machine to move rearwardly of the base on wheels 50 and 51 to the retracted or loaded position shown in Fig. 2. Conversely, when the machine is advanced upwardly of the inclined base to a position where the wheels engage the depression it is accurately positioned to permit passage of the pivot pin 10 through the bearings and sub-base. Balancing of the machine with respect to the sub-base support is readily accomplished by movement of the boring unit in its base.

Means controlling swinging movement of the machine on pivot pin 10 consists of cable 62 having one end fixed to the sub-base at 63 from whence it passes downwardly around sheave 64 rotatably mounted on base 3 and rearwardly over sheave 65 at the rear end of the sub-base and then downwardly around a winding drum 66 on shaft 67 journaled in parallel spaced up-

right channel members 68 and 69. The shaft 67 also carries toothed wheel 70 and chain sprocket 71 driven by chain 72 trained over a driving sprocket 73 on shaft 74 carrying at one end hand wheel 75. Rotation of the toothed wheel in one direction is normally prevented by the manually operable pivoted dog 76 on shaft 71 journaled in bearings fixed to the flanges of the channels. The dog is so designed and positioned that its weight tends to swing it downwardly into engagement with the periphery of the toothed wheel.

The structural arrangement described provides for adjustment of the boring unit with its base and sub-base to a retracted or loaded position as illustrated in Fig. 2 or to a forward or controlled angle pivotal position on pivot pin 10 as shown in Figs. 1 and 6 in particular. When the boring machine is in the position shown in Fig. 6 or in the dotted line position of Fig. 1, it occupies a position permitting substantially perpendicular boring operations or those provided for by the lateral swinging movement of the machine on the king bolt 55 and the fixation of the machine in a position of adjustment by the latch bolts 60 detachably engaged in the receiving apertures of member 57.

Controlled angle adjustment on pivot pin 10 at right angles to the swinging adjustment permitted by bolt 55, and from the vertical position shown in Fig. 6, is effected by the removal of pin 11 and by winding the cable 62 on the drum 66 by operation of hand wheel 75. The tension applied to cable 62 serves to swing the machine downwardly from the vertical and angular positions shown in Fig. 1 to an inclined position wherein the wheels 50 and 51 on the sub-base engage in the depressions 16 in the inclined upper angles of base 3. The machine can be fixed at controlled angles in this swinging movement by restoring the locking pin 11 by passing it through selected ones of apertures 78 in the arms 61 and aligned holes in the base. This provides positioning of the machine for controlled angle boring operations from a position inclined above the horizontal to a substantially vertical position as illustrated in Figs. 1 and 2, and in an intersecting arc provided by lateral swinging adjustment on the bolt 55 and locking engagement of the latch bolts 60.

Extremely accurate progressive earth borings may be made in any selected positioning of the machine by the power driven boring unit 17 and auger 18, under sensitive manual control afforded by the feeding means previously described. The auger 18 is preferably of the self-clearing type described and claimed in my copending application Serial No. 288,237, filed Aug. 3, 1939, having a detachable cutter head 79 and one or more auger sections 80 with spaced spiral flights having reaming cutters at their forward end. However, the auger structure forms no part of the novelty in this invention except as a necessary element and other augers may obviously be employed. At the commencement of a drilling operation the boring unit is in a retracted position in its guiding base, from which position it is advanced as drilling conditions permit by operation of the hand wheel 43 until it becomes necessary to add another auger section. Successive auger sections may be added by disconnecting the boring unit from already inserted tool sections and feeding it rearwardly of the base to receive an interposed tool section, after which the progressive drilling may be resumed.

Tool sections are withdrawn in a reverse of these operations.

When the boring machine occupies the position with wheels 50 and 51 engaged in the depressions 16 of the base, the pivot pin 10 can be withdrawn or inserted. Thus, when the machine is swung downwardly with the wheels in engagement with the base, the pivot pin can be withdrawn to release the machine for rearward movement down the inclined base to the retracted or loaded position shown in Fig. 2. Conversely, when the machine is advanced from its retracted position to the point where the wheels engage the base depressions in the sub-base it is in the proper position for insertion of pin 10 to provide pivotal movement of the machine in controlled angle drilling operations. The control cable 62 and its cooperating sheaves may be so arranged that forward movement of the machine from its retracted position can be accomplished to a certain point by tension applied to the cable.

The structural arrangement is such that the power driven boring unit must have considerable latitude of movement in its swinging and reciprocating positions. In order to permit this movement, the boring unit is driven by an automatically adjustable independent motor or power plant 81 pivotally and adjustably supported in elevated position on the mobile support 2. The illustrated embodiment consists of the motor 81, clutch and gear transmission 82 and flexible drive shaft 32, the latter affording power transmission between the motor and the boring machine. The motor is pivotally supported on a wheeled base 83 consisting of rear wheels 84 rotatably mounted on the base consisting of spaced channel members 85, deck 86 welded thereto, and the front welded inverted tie member 87. Tie member 87 carries at its central point the rotatably mounted yoke 88 which in turn rotatably supports front wheel 89. The yoke 88 has fixed thereto the second yoke 90 detachably associated with handle 91. The deck or top 86 is centrally apertured to receive king pin 92 and carries anti-friction rollers 93 mounted in bearings on the under side of the deck. Peripheral portions of the rollers extend through apertures 95 in the deck so as to lie slightly above the deck to provide contact bearing support for a base plate 96 on the motor, said base plate being centrally apertured to accommodate king pin 92.

The motor and its pivotally associated wheeled base, by which the motor can be transported when separated from the machine assembly, is detachably mounted in elevated position with respect to base 2 on the adjustably mounted supporting frame 97 consisting of parallel longitudinally extending channels 98, upright angle members 99, and angle tie members 100, having inwardly facing flanges to receive the wheeled base which is detachably connected therewith by the pins or bolts 101. The elevated supporting frame is receivable for longitudinal adjustment between the spaced parallel angles 102 fixed to the movable support. The angles are provided with a line of apertures to receive anchor pins 103 which pass through the angles and apertures in the channels 98 to fix the supporting frame in the desired position of adjustment. In this arrangement, the elevated pivotal support of the motor allows automatic swinging adjustment of the motor and flexible shaft in all of the extensive movements of the boring machine.

In the described structural organization, the boring machine unit and power connections are required to have considerable latitude of movement to accommodate the swinging movement of the machine in intersecting planes and its reciprocating movement in the channel trackway. The motor automatically adjusts itself angularly in response to movements of the boring machine for proper application of power through the flexible drive. The wheel base for the motor affords means of transportation when it is found necessary to dismount the motor from its structural organization supported by the vehicle. The machine base is illustrated in position at the rear side of the vehicle support. It will be obvious that this base can be shifted 90° in overlying relation to the adjacent side of the vehicle support.

The operation of the apparatus is as follows. The boring machine is normally carried in the retracted or transporting position shown in Fig. 2. With the positioning of the transport vehicle for a drilling operation, the drilling machine is forced upwardly along the inclined surface of the base until the wheels 50 and 51 engage in the base depression. Forward movement of the machine may be attained by tension applied to the cable. Such forward movement by the cable is possible until the sheave at the end of the sub-base engages the underside of the cable. When the machine is in the position with the wheels engaged in the base depressions, it is in the exact position to be pinned to the front end of the base by passing the pivot pin through the sub-base frame and the bearings on the base. In the pinned position the machine and its sub-base can be swung downwardly from its position inclined above the horizontal to a substantially vertical position for effecting substantially perpendicular drilling operations. The machine automatically adjusts itself to a perpendicular position by means of its pivotal support on the sub-base. It can be fixed in this or an adjusted angular position by the latch bolts. The machine may be further anchored against a transverse swinging movement by fixing the adjustable arms 61 to the base by the through pin 11. Adjustment of the machine for drilling operations in inclined positions above the horizontal is obtained by removing the locking pin 11 and by swinging the machine and its sub-base by the manually operated cable winding mechanism. When a desired position of adjustment is reached, the pin 11 is again passed through the selected apertures in the supporting arm and that in the base.

The boring unit is advanced or retracted in its base by the manually operated feed means previously described. This feed means allows also for balancing the machine in adjustment operation. When a boring operation is completed, the machine and its sub-base is swung downwardly by the cable tensioning means until the wheels again engage the depressions in the base. In this position, the pivot pin 10 can be removed to allow the machine and sub-base to be retracted downwardly of the inclined base to the loaded position.

The structural organization provides for controlled angle drilling along the highways, under existing structures and wherever points are accessible to the self-propelled carrying support and it is to be noted that the multiple swinging adjustments in intersecting arcuate paths, together with the reciprocating movement of the

boring unit, provide a large field of operations.

While the invention has been described in connection with the preferred embodiment thereof, it is to be understood that the words which have been used are words of description rather than of limitation, and that practice of the invention within the scope of the appended claims, may be resorted to without departing from the true scope and spirit of the invention in all its aspects.

I claim:

1. In combination with a mobile carrier having a substantially horizontal platform support, a machine base fixed to said support in overhanging relation at one side thereof, an earth boring machine comprising a channel guide support and a boring unit connected therewith for longitudinal movement in the channel support, means movable between a rear position on said base and a forward pivotal position for supporting said machine on said base for compound pivotal movement with respect to said base, whereby said machine can be adjusted for angular drilling operations, means including a manually operable feed mechanism for reciprocating said machine with respect to said base in drilling operations, and means for driving said machine, said driving means being so constructed and arranged as to be self adjustable in response to movements of the boring machine.
2. In combination with a self propelled vehicle having a substantially horizontal support, an earth boring machine pivotally mounted on said support at one side thereof for vertical swinging adjustment in relation to the support, means for driving said earth boring machine, and means adjustably mounting said driving means in elevated position with respect to said support, said last mentioned means including a pivotal connection for automatic adjustment of said driving means in response to movements of the boring machine.
3. In combination with a vehicle having a substantially horizontal platform support, an earth boring machine, means for mounting the machine on said support at one side thereof for vertical swinging adjustment in relation to said support, said means including a base fixed to said support and an intermediate base movably connected therewith means for driving said machine, and means pivotally mounting said driving means on said support in elevated position for automatic angular adjustment in response to movements of the boring machine.
4. In earth boring apparatus of the character described, a horizontal supporting base, a machine supporting frame pivotally mounted for vertical swinging movement on said base, an earth boring machine having a channel base trackway and a boring unit slidably mounted therein for movement longitudinally of the trackway, means pivotally connecting said supporting frame and said earth boring machine for relative angular adjustment, means for locking said machine and frame in a desired position of adjustment, and means pivotally mounted on a vertical axis for driving said machine, said driving means being self adjusting in response to movements of said machine.
5. In earth boring apparatus of the character described, a substantially horizontal base support, an intermediate frame pivotally mounted for vertical swinging movement at one end of said support, adjustable means for locking said frame and support in a desired position of

angular adjustment, an earth boring machine pivotally connected with said frame for swinging angular adjustment thereon transversely of the plane of said vertical swinging movement, releasable means for locking said machine and frame in a desired position of adjustment, means for driving said machine, and means for pivotally supporting said driving means for angular adjustment in response to movements of the boring machine.

6. In earth boring apparatus of the character described, a substantially horizontal base support, an intermediate frame pivotally mounted for vertical swinging movement on said support, adjustable means for locking said frame in relation to said support in a desired position of angular adjustment, an earth boring machine pivotally connected with said frame for swinging angular adjustment thereon, releasable means for locking said machine and frame in a desired position of adjustment, a manually operated mechanism for effecting a vertical swinging motion of said frame and earth boring machine on the base support from a substantially vertical position to a position upwardly inclined with respect to said support, and driving means for said machine pivotally mounted to follow movements of the machine.

7. In combination with a vehicle support, a machine base fixed to said support, said base having spaced parallel upwardly inclined members having aligned depressions therein spaced from the ends of the members, a machine supporting base frame having spaced wheels adapted to ride on said inclined members, connecting means including a removable pivot pin for pivotally mounting said base frame for vertical swinging movement at one side of said machine base, said wheels and said depressions being equidistant from the pivot pin so as to engage when the wheels are swung downwardly to engage the base, manually operable means for effecting

swinging of said base frame to effect an angular adjustment thereof with respect to the machine base, and adjustable means for fixing said base frame in the desired position of adjustment.

5 8. In combination with a vehicle support, a machine base fixed to said support, said base having spaced parallel upwardly inclined members having aligned depressions therein spaced from the ends of the members, a machine supporting base frame having spaced wheels adapted to ride on said inclined members, connecting means including a removable pivot pin for pivotally mounting said base frame for vertical swinging movement at one side of said machine base, said wheels and said depressions being equidistant from the pivot pin so as to engage when the wheels are swung downwardly to engage the base, manually operable means for effecting swinging of said base frame to effect an angular adjustment thereof with respect to the machine base, adjustable means for fixing said base frame in the desired position of adjustment, a boring machine pivotally connected with said base frame for lateral swinging adjustment with respect to the base frame, and releasable means on said machine and base frame for anchoring the machine in the desired position of adjustment.

20 9. In combination with a mobile carrier having a substantially horizontal platform support, a machine base fixed to said support having an end thereof at one side of the support, an earth boring machine comprising a channel support and a boring unit connected therewith for slideable longitudinal movement in the channel support, means supporting said boring machine on the machine base for pivotal movement at the end thereof, means for driving said machine, and means providing automatic angular adjustment 25 of said driving means in response to movement of the boring machine.

30 ALAN JAY PARRISH.
